UNITED STATES PATENT OFFICE

STERLING C. MACK, OF BANGOR, PENNSYLVANIA, ASSIGNOR TO JULIUS KAYSER & CO., OF NEW YORK, N. Y.

KNITTING MACHINE

Application filed June 6, 1931. Serial No. 542,528.

This invention relates to a hosiery knitting machine of the so-called full-fashioned or flat type having a plurality of banks of needles, each bank being capable of knitting a separate stocking leg or other fabric; and this invention relates more particularly to the control means for the carrier-rods which extend from end to end of the machine and upon which are mounted the various thread-carriers.

10 One object of my invention is to provide improved means for limiting and controlling the movement of the carrier-rods and for preventing excessive vibration therein.

15 A further object of my invention is to provide damping means at the ends of the machine for engaging the ends of the carrier-rods just before the latter are brought to rest.

20 A still further object of this invention is to provide a hinged or pivoted member for engaging the carrier-rods at both ends of the machine for preventing excessive vibration due to the sudden stoppage of the rods.

25 With these and other objects in view the invention consists in the novel construction and arrangement hereinafter described illustrated in the accompanying drawings and particularly pointed out in the appended claims, it being understood that various 30 changes may be made in the structural details and in the arrangement of parts to control the various carrier-rods and to suit the varying forms of heels and other reinforcements or ornamentations being knitted into the 35 stocking.

35 Referring to the drawings in which similar reference numerals designate like parts in all views, Fig. 1 is a front view showing a carrier-rod with certain parts of the machine 40 in combination with a damping device according to the present invention at each end of the rod; Fig. 2 is a plan view showing a group of seven carrier-rods with control means therefor; Fig. 3 is a cross section of 45 the carrier-rods showing my device—in side view—applied thereto; Fig. 4 is a similar view but showing one of the rods in engagement with the device; Fig. 5 is a sectional view of the carrier-rods and of the device at 50 the opposite end of the machine; Fig. 6 is a

perspective view of the swinging part of the device shown at Fig. 5; Figs. 7, 8 and 9 are perspective views showing the different forms of the ends of the carrier-rods for cooperation with this device and Fig. 10 is 55 an end view—partly in cross section—showing the mechanism for actuating the feed screw for controlling the movement of the carrier-rods.

Referring to the drawings, the carrier-rods 11 extend the full length of the machine in the usual well known manner and are guided in grooves in a bed plate or guide frame 12. These rods 11—or certain of them—are equipped as desired with thread-carriers 13 with the usual well known operating mechanism as commonly employed in such machines and with abutment or stop devices 14 of the well known form for co-operation with the usual abutment members 15 which are screw-threaded internally for engagement upon the usual right and left hand feed screw 16. For varying the travel of certain of the carrier-rods 11, the screw 16 is rotated so as to move the members 15 towards or away from each other in the well known manner, and—in accordance with the arrangement shown at Fig. 10—the feed screw 16 has secured thereon a ratchet wheel 17 engaged by a pawl 18 pivoted to an arm 19 and actuated by a rod 20 which latter is pivotally connected to the arm 19 and to a lever 21 fulcrumed on a bracket 22' on the frame 22 of the machine; the said lever 21 being operated by means of a cam 23 which engages a roller 24 on said lever while a spring 25 serves to retain the roller 24 in engagement with the face of the cam 23. The abutment members 15 are also shown at Fig. 10 and are adapted to cooperate with abutment stops 80 such as 14 on the various carrier-rods or on certain of such rods in the usual well known manner.

My damping or controlling devices 26, 27 are located at the left and right hand ends of 95 the machine, respectively, and are similar except that the swinging members 28, 29 thereof are shaped at their underside to suit requirements and to engage the proper rods 11, and these swinging members 28, 29 are inter- 100

changeable and are readily removable so that the machine may be quickly and conveniently adapted for different classes of work—for the knitting of stockings or other fabrics having different forms of heel reinforcements or ornaments or other modifications requiring varying movements of the individual carrier-rods.

The device 27 is shown at Figs. 3 and 4 of the drawings, is located at the right hand end of the machine and consists of a carriage or hollow body part 30 open at its lower side and recessed internally at 31 and 32 to engage the front and rear edges, respectively, of the bed plate or guide 12 for the rods 11, and secured by means of screws 33, 34 to the lower parts of the body 30 are guide plates 35, 36 which engage the underface of the said bed plate 12 so that the device 27 may slide longitudinally upon said member 12. Mounted upon a pivot pin 37 in the upper part of the body 30 is the swinging member 29 whose free end extends beyond the body 30 and has on its lower face an eye 38 for engagement by a spring 39 whose opposite end is attached to a pin 40 projecting from a bracket 41 secured on the front face of the body 30 so that the spring 39 tends to hold the member 29 in its lower position as shown at Fig. 3 while the member 29 is free to ride into the position shown at Fig. 4 when one of the rods 11 engages a depending nose or cam piece 42 on the underside of the member 29.

The carrier-rods 11 are shaped at their ends with square extremities 43—Fig. 7—or with bevels or inclines 44—Fig. 8—or with bevels 44 in combination with upper recesses 45—Fig. 9—to suit the particular purpose for which the various rods are employed. The underpart of the swinging member 29 is formed (Figs. 3 and 4) with a square depending part 46 adapted to serve as a stop or abutment for the square end 43 of one of the carrier-rods 11 and the arrangement is such that the cam piece 42 is engaged by the bevelled end or incline 44 of one of the other carrier-rods and when the member 29 is raised by the engagement of the carrier-rod with the cam piece 42, the abutment member 46 is out of the path of the carrier-rod corresponding thereto so that this abutment is effective only when the member 29 is in its lower position.

The device 26 is similar to the device 27 but the swinging member 28 shown at Fig. 5 has a nose or cam piece 47 adapted to be engaged by one or other of two of the carrier-rods 11 and has an abutment piece 48 to serve as a stop for one of the carrier-rods when neither of the two aforementioned rods is in engagement with the cam piece 47.

When it is desired, however, to utilize an abutment member such as 46 or 48 while a nose or cam piece such as 42 or 47 is above one or more of the carrier-rods, the latter are formed as shown at Fig. 9 with a recess 45

into which the cam piece 42, 47 may fall to permit the abutment 46 or 48 to move into the path of the carrier-rods corresponding thereto.

In order that the devices 26, 27 may function at the proper time, it is necessary that they be displaced longitudinally of the guide member 12 and for this purpose each of the devices 26, 27 is connected with one of the abutment members 15, by means of a rod 49 which is screwed into a socket in the member 15 and is secured by means of a lock-nut 50 while the opposite end of said rod passes through a bore in the rear part of the device 26 or 27 and is clamped to such device by means of lock-nuts 51, 52 so that the motion of the feed screw 16 displaces the devices 26 and 27 together with the abutment members 15, and the lock-nuts 51, 52 permit easy and convenient adjustment of the said devices relatively to the abutment members to which they are attached.

From the foregoing it will be understood that the swinging members 28, 29 are adapted to cooperate with one or more of the carrier-rods according to the nature of the fabric being produced by the machine and from time to time the said members may be interchanged or replaced to suit requirements and to provide for the proper movement and stoppage of the carrier-rods cooperating therewith. The damping action of the spring loaded members upon the bevelled or inclined ends of the rods eliminates, or greatly reduces, objectionable shock and vibration, and permits greatly increased speeds of operation even when the reinforcing threads of the heel portions of a stocking are being laid in and the rods carrying these threads have only a very short travel.

Although the drawings and above description disclose the best mode in which I have contemplated embodying my invention, I desire to be in no way limited to the details of this disclosure for in the further practical application of my invention, many changes in the form and construction may be made as circumstances require or experience suggests without departing from the spirit of the invention within the scope of the appended claims.

What I claim is:—

1. In a flat knitting machine having a plurality of thread-carriers, a plurality of carrier-rods, in combination with a damping device comprising a yielding member and means on said member for engaging the ends of the carrier-rods for preventing excessive vibration thereof, and additional means on said member to serve as an abutment for certain of the carrier-rods.

2. In a flat knitting machine having a plurality of thread-carriers, a plurality of carrier-rods, guides for said rods and a device mounted on said guides to engage the ends

- of the rods to prevent excessive vibration thereof, and carrier-rod abutments on the device. 10
3. In a flat knitting machine having a plurality of thread-carriers, a plurality of carrier-rods, stop means for the rods, and a device comprising a yielding member and means on said member for engaging certain of the rods to serve as abutments and for engaging other rods to damp vibration therein on sudden stoppage thereof. 15
4. In a flat knitting machine having a plurality of thread-carriers, carrier-rods therefor, abutment stops on said rods, and a movable carriage comprising a swinging member, a carrier-rod abutment on the said member, surfaces on said member for engaging the ends of certain of the rods, and means to hold the said surfaces upon the rods to damp the vibration therein. 20
5. In a flat knitting machine having a plurality of thread-carriers, a plurality of carrier-rods therefor, stop means on certain of the rods, and a spring loaded swinging member for engaging the ends of certain rods to eliminate vibration and for engaging the ends of certain rods to serve as abutments therefor. 25
6. In a flat knitting machine having a plurality of thread-carriers, a plurality of carrier-rods therefor, bevelled ends on certain of the rods, square ends on certain of the rods, and a movable member at the end of the machine comprising a cam piece for engaging the said bevelled end, and an abutment member for engaging the square end, for the purpose described. 30
7. In a flat knitting machine having a plurality of thread-carriers, a plurality of carrier-rods therefor, bevelled ends on certain of the rods, square ends on certain of the rods, bevelled and recessed ends on certain of the rods, and a yielding member at the end of the machine comprising a cam piece for engaging the said bevelled ends, and an abutment piece to engage said square ends and to enter said recess. 35
8. In a flat knitting machine having a plurality of thread-carriers, a plurality of carrier-rods, guide means for the rods, stop means for the rods, and a device mounted on said guides at each end of the machine and comprising a yielding pivoted member and means on said member for engaging certain of the rods to damp vibration therein and for engaging certain other rods to serve as abutments therefor. 40
9. In a flat knitting machine having a plurality of thread-carriers, carrier-rods therefor, abutment stops on said rods and a movable carriage at each end of the machine comprising a swinging member, a cam on said member for engaging the ends of certain of the rods and a spring device to hold the said cam upon the rods to damp the vibration 45
- therein and a rod abutment member on said member. 50
10. In a flat knitting machine having a plurality of thread-carriers, a plurality of carrier-rods therefor, stop means on certain of the rods, and at each end of the machine a spring loaded swinging member for engaging the ends of certain rods to eliminate vibration and for engaging the ends of certain other rods to serve as abutments therefor. 55
11. In a flat knitting machine having a plurality of thread-carriers, a plurality of carrier-rods therefor, bevelled ends on certain of the rods, square ends on certain of the rods, bevelled and recessed ends on certain of the rods and at each end of the machine a movable member comprising a cam piece for engaging the bevelled ends and the said recess and an abutment piece for engaging said square ends. 60
12. In a flat knitting machine, having a series of thread-carriers, a plurality of carrier-rods, abutment members thereon, a carriage at each end of the machine, a spring loaded damping device on the carriage for engaging certain of the rods, abutment means on the said device for engaging certain of the rods, and means for automatically feeding the said carriage longitudinally of the rods to control the movement thereof. 65
